(57) **CLAIM**

The ornamental design for a bottle, as shown and described.

DESCRIPTION

FIG. 1 is a front elevational view of the claimed design, the rear elevational view being identical.

FIG. 2 is an elevation of the right side thereof, the left elevation being identical.

FIG. 3 is a perspective view of the front and left side thereof, the rear and right side perspective being identical; and,

FIG. 4 is a top plan view thereof.

The broken-line disclosure in the views is for illustrative purposes only and forms no part of the claimed design.
